UNITED STATES PATENT OFFICE.

THOMAS A. KNOWLTON, OF BOSTON, MASSACHUSETTS.

DESIGN FOR AN ORNAMENTAL STAND.

SPECIFICATION forming part of Design No. 29,886, dated December 27, 1898.

Application filed December 5, 1898. Serial No. 698,376. Term of patent 3½ years.

To all whom it may concern:

Be it known that I, THOMAS A. KNOWLTON, citizen of the United States, and a resident of Boston, in the county of Suffolk and State of Massachusetts, have invented and produced a new and original Design for an Ornamental Stand, of which the following is a specification.

The drawing shows in perspective an ornamental stand illustrating my design.

The leading feature of my design for an ornamental stand comprises an upright central hilt in the similitude of a bayonet-hilt surmounted by a tubular holder and terminating at its lower end in an offset depending blade-like extension bent in spiral form to constitute a base. The upright central shaft a of the stand is made in the fashion of a bayonet-

hilt, with the offset blade-like extension a' depending therefrom and bent in spiral form 20 at a^2 to constitute a supporting-base. A tubular holder a^3 is held in and surmounts the hilt-like central shaft a of the stand.

The design presents a unique and attractive appearance to the eye. 25

Having fully described my design, what I claim is—

The design for an ornamental stand, substantially as herein shown and described.

In testimony whereof I have signed my 30 name to this specification in the presence of two subscribing witnesses.

THOMAS A. KNOWLTON.
